UNITED STATES PATENT OFFICE.

DOOR E. FELT, OF CHICAGO, ILLINOIS.

CALCULATING-MACHINE.

1,028,344.

Specification of Letters Patent.

Patented June 4, 1912.

Application filed November 28, 1911. Serial No. 662,300.

To all whom it may concern:

Be it known that I, DORR E. FELT, a citizen of the United States, residing in Chicago, in the county of Cook and State of Illinois, have invented a new and useful Improvement in Calculating-Machines, of which the following is a specification.

My invention relates to calculating machines provided with keyboard mechanism, embodying a plurality of keys of different orders whose manipulation determines the amounts added, and particularly to the multiple order key driven duplexing calculating machine such as the well known comptometer set forth in my prior United States Patents, Nos. 762,520 and 762,521 of June 29, 1904; 767107 of August 9, 1904, No. 960528 of June 7, 1910 992950 of May 23, 1911 and 996009 of June 20, 1911.

The invention has for its object the providing of such a calculating machine with improved means for normally locking the keys of such lock continuing in full force except when the keys are given complete strokes and during the ensuing upstrokes following such complete strokes, so that incomplete key strokes do not cause any release of the lock and consequently the operator making such incomplete stroke will be prevented from proceeding with his computation without first correcting the error.

Another object has been the providing improved mechanism for controlling the accumulator wheels and for obtaining more perfect control of the numeral wheels.

The invention consists in the novel construction of parts and devices, and novel combinations of parts and devices herein-after set forth.

In the accompanying drawing forming a part hereof, Figures 1 and 1^a are unitedly a longitudinal vertical section of a key driven calculating machine embodying my present invention. Fig. 2 is a similar section of a portion of the machine showing the 9 key depressed. Fig. 2^a is a detail of the mechanism for locking the keys showing the releasing means. Figs. 3, 4, 5, 6, 7, 8, 9, 10 are sections on the lines 3—3, 4—4, 5—5, 6—6, 7—7, 8—8, 9—9 and 10—10 respectively of Fig. 1. Fig. 11 is a detail sectional view of one of the keys. Fig. 12 is a detail of the

catch for moving the detent which locks the accumulator wheel after partial strokes by the keys. Figs. 13 and 14 are detail views of the stop levers and Fig. 15 is a similar view of the partial stroke lever. Fig. 16 is a side elevation of the machine. Fig. 17 is a sectional view showing one of the stop levers for arresting the accumulator wheel; Fig. 18 shows a cam arm forming part of the canceling mechanism. Fig. 19 shows one of the accumulator wheels. Fig. 20 is a section similar to Fig. 1 with some of the parts omitted for the sake of clearness. Figs. 21 and 22 are detail and detached views of the column actuator arresting devices.

In said drawing, 20 represents the numeral or register wheel of one denomination driven by the gear 21 from the accumulator wheel 22 which embodies a gear meshing with the gear 21. The accumulator is connected by a pawl in the customary way in machines of this kind, to the ratchet 23, and fast upon such ratchet is a pinion 24 meshing with the teeth 25 on the front end of the column actuator 26 pivoted on the shaft 26^a at the rear of the machine, the ratchet and pawl being adapted to communicate motion to the accumulator only when the column actuator moves up, and to turn idle without moving the accumulator when the actuator is being depressed. Parallel with the actuator are two stop levers 27 and 28 pivoted at the rear of the machine on a cross shaft 29, and acting to throw one of the stops 27^a or 28^a shown detached at Figs. 21 and 22, and pivoted on a stationary cross rod 27^b into engaging position relative to the coarse teeth on the rear face of the vertical portion of the actuator, and thus to arrest the actuator when the keys have reached the ends of their strokes, the operation being fully described in said Patent 762520. A third lever 30 also parallel to the actuator is pivoted on the shaft 26^a and I designate it as the auxiliary or partial stroke lever. It is operated with each stroke given the keys and its function will be understood from the following parts of this specification. The keys of the machine are shown at 31, and they are provided with lifting springs 32 at the bottom and are also pro-

vided with some features of Patents 982416 and 982417 as will be understood from the description below. The column actuators are provided with lifting springs 33 as in the usual construction.

5 The accumulator provided in each order of the machine rotates in one direction only as will be understood from what is above written, and is locked normally against 10 movement in this direction by the detent 37 hereinafter described except when that detent is withdrawn by reason of a full stroke given one of the keys in the order to which the accumulator belongs. The accumulator 15 embodies a lantern portion the pins of which are shown at 34 in Fig. 2, and these pins engage the back stop 35 for preventing backward rotation, and they also engage the carrying detent 36 whereby the accumulator is 20 rotated at proper times in carrying, Figs. 2 and 20. The lantern pins further engage said detent 37 whose normal position is a locking one between the pins but is withdrawn from that position at the conclusion 25 of each full downward stroke received from any of the keys. The detent 37 is pivoted at 38 upon the bell crank carrying member 37^a, a spring 39 at its foot tending to keep it away from the accumulator, and a pin 39^a 30 projecting from the member 37^a into the opening 39^b limits its movements, but it is controlled as to position by a catch 40 which is one of the novel features of the mechanism and which is pivoted at its upper 35 end on a stationary pivot 41, and having a dolly roll 42 on one side adapted to be engaged by the stop lever 28 when that lever is depressed at the same time with the column actuator through the action of an 40 even number key, or by the stop lever 27 when the actuator is depressed by an odd number key. The catch is also provided with a right angle lip or flange 43 at its foot extending toward the detent 37 and the 45 detent 37 is provided with a lip or tongue 44 projecting toward the catch. The lip 43 and tongue 44 are adapted to act as guides to each other when they come in contact, allowing them to move one upon the other 50 without effecting any arrest of one by the other, excepting as specified below and they are clearly shown at Fig. 5, and when at rest the catch and detent are in the relative positions shown at Fig. 1, with the detent entered 55 between the pins of the accumulator, and with the lip and tongue in position to engage. If now a key be depressed a full stroke, the parts move to the position of Fig. 2, the catch being depressed by one of the 60 stop levers so that it relieves the detent from the engagement of the lip and tongue, sufficiently to permit the detent to retract from the accumulator, thus leaving the accumulator free to be turned by the ratchet 23. At 65 the conclusion of the key stroke, the column

actuator rises to its normal position, and in such movement the dolly roll 46 carried by it, engages the underside of the detent 37 and lifts it again to its position between the pins of the accumulator, the catch also resuming its original position under the power of its spring 47.

70 It will be noted from the above that when the mechanism is standing still, the numeral wheels are always locked, and thus safeguarded against accidental movement due to jarring, shock, or change of position.

75 In case the stroke of the key is only a partial one, the stop lever actuated thereby will not move so far if at all as in full strokes, 80 and consequently will not cause the catch to move far enough to release the detent from the accumulator, but on the contrary the detent will remain in its locking position in the accumulator so that the latter cannot 85 turn. And as the other orders in the machine are all locked at the same time by the partial operating of the key mentioned as we shall presently see, the operator must now correct the error before proceeding with 90 his computation. The mechanism for thus locking the other orders will be described in a later part of this specification.

95 My invention contemplates the effecting of two separate and novel locks upon the column actuators. The first of these acts normally, and its main purpose is the prevention of partial strokes of the keys through the accidental contact by the operator's finger with keys adjacent upon the 100 right or left of the ones intended to be struck. Such accidental pressure upon the adjacent keys will not cause even partial strokes by them, because of the construction of the keys in parts, with a non-depressible 105 outer portion, as hereinafter explained, and because such outer portion encounters the column actuator which is normally locked by the engagement of upstanding hooks 50, with which each actuator is provided, with 110 lateral projections 51 on the vertical levers 52, which are novel in this mechanism and are shown at Fig. 1 as locking the actuator, of which there is one in each order of the machine, such levers being pivoted on a stationary pivot near the top plate of the machine. The lever 52 has an offset 54 near its 115 vertical center forming a seat for the dolly roll 55 on the lever 30, and the lever 52 is impelled forward in the machine by a spring 120 56. The dolly roll 55 moves the lever 52 backward whenever lever 30 is depressed, and in so doing releases the lock between hook 50 and projection 51, the roll moving 125 from its rest in front of lever 52 to the lower straight face of that lever. The other lock upon the actuator is one which is set in operation whenever partial or incomplete 130 strokes are given the keys and is best shown at Figs. 1, 2, 2^a and 20. The mechanism em-

ployed in it is substantially the following: The lever 52 carries a rearwardly extending flat connection 57, the forward end of which is bent down and pivoted to the lever at 52^a, and to this bent end the spring 56 is attached, so that the rear end of the connection is always pressed down. Said rear end extends over and at times rests upon a square rod or bar 58, supported transversely of the machine in swinging arms 59 pivoted stationarily at 60. The rod 58 is adapted to be shifted bodily forward and back a limited distance as its ends are passed into openings 62 larger than its cross section, in the stationary frame 63 and as it extends from side to side of the machine, it is adapted to be operated, not only by the connection 57 above mentioned, but all similar connections in the other orders of the machine. For thus shifting the bar 58, each connection 57 is provided with a downward bend 61 in that portion of its rear end which is bent at right angles as shown, and this bend is provided on its forward edge with a slight projection 61^a, adapted when the connection rests on the bar 58 to engage the bar, so that when the connection is retracted to its forward position, as hereinafter described, it will carry the bar forwardly with it to the extent permitted by the stationary arms 63.

Each column actuator is provided with an upstanding projection 64 under the point of the connection 57, so that when the actuator is in its normal position the projection 64 lifts the connection above the bar 58 as seen at Figs. 1 and 2^a but when the actuator is depressed by a key as for instance as in Fig. 2, then the connection 57 drops onto bar 58 and engages it in readiness for the next retracting movement of the connection. The actuators are each further provided with upstanding hooks 65 back of the projections 64, and these hooks are adapted to engage with depending swinging hooks 66 in each order of the machine. The hooks 66 are supported by holders 67 all mounted on a shaft 68 extending across the machine through all the numeral orders therein. A spring 69 extends from each holder 67 toward the front of the machine and is there attached to a stationary wire 70. These springs 69 tend to draw the holders to which they are attached in the direction they must move to carry their hooks 66 which normally stand at an angle as in Fig. 1, into engagement with the actuator hooks 65. Said springs also tend to create pressure by the lips 71 of the holders on the cross rod 72 arranged transversely of the machine and parallel to shaft 68 and supported in levers 73, of which there are two at the sides of the machine and all pivoted at 74 upon the rock bar 75 extending across the machine. Other springs 76 extend from the

square bar 58 to the shaft 68 and draw these parts together.

If the stroke given to the key is only a partial instead of a complete one, the actuator does not return to normal position when the hand is withdrawn from the key because the accumulator is locked by the detent 37 and prevents it, but the partial stroke lever does return, and in so doing its dolly roll 55 releases its pressure on lever 52 so that the latter moves forward to its normal position, carrying with it the connection 57 and the square bar 58. When this change of position takes place, the spring 56 attached to connection 57, pulls the latter forward, thereby taking the square bar 58 with it, since the rear end of the connection 57 is already in its lower position and in engagement with bar 58. As bar 58 moves forward, the forward ends of levers 73 are thereby allowed to fall, whereupon the pressure of the lips 71 on cross bar 72 is relaxed. This allows springs 69 to act on the holders 67 and thereby swing the hooks 66 into engagement with the hooks 65 of all the actuators except that in the order containing the key which was partially struck. To complete the stroke of that key, the operator being unable to proceed with his computation, first proceeds to correct the error by completely depressing the partially operated key. Upon withdrawing his finger from the key after so doing, the actuator of the order containing the key will automatically return to normal and its hook 65 will at once engage with the hook 66 of the same order, and thus become locked in common with the actuators of the other orders. To unlock the machine which has become locked in this manner, I provide a key 80 which engages a cross rod 81, mounted on one of the levers 73 as plainly indicated in Fig. 2^a, so that pressure upon said key will cause the instant disengagement of all the hooks 66 from the hooks 65, so that the operator may then proceed with his computation as though no incomplete stroke had been given any key. I also provide the canceling mechanism with means for unlocking the machine so that the operator has a choice of means for accomplishing that result, though in case the canceling mechanism is employed all the numeral wheels will be returned to zero at the same time the actuators are unlocked, and of course this may not always be desired.

In Figs. 16, 17, 18 and 19 I have illustrated so much of the canceling mechanism as is needed to understand its connection with the unlocking operation. In Fig. 16, 90 represents the canceling lever, mounted on rock shaft 91, arranged transversely of the machine, and operating the segmental slotted cam 92 whose curvilinear slot 93 engages the dolly roll 94 on the rear end of 130

the canceling segment lever 95 which is pivoted at 96 and has formed on its front end the segment gear 97 meshing with the pinion 98 on the same shaft which supports the intermediate gears 21 of the numeral wheel mechanism. Swung on arms from the rock shaft 91 are dolly rolls 99 engaging the open cam slot 100 in the free ends of the cam arms 101, pivoted at 102 and said dolly rolls 5 also engage the rear ends 103 of the stop controlling elbow levers 104 pivoted at 102 and whose lower and forward ends are in engagement with connections 106 fixed to the canceling lever rock bar 107, supporting 10 a series of upright hook stop levers 105 one for each denomination, that are swung forward by the rocking of said bar 107 to stop the pins 108 on the pinions 109. The operation of the canceling lever rocks the levers 15 104 on their pivot and causes thereby the rocking of the bar 107 so that the levers 105 stop the pinions 109, all as described in Patent No. 960528 to me of June 7, 1910. Said elbow levers 104 also carry upwardly 20 extending arms 110 as seen in Fig. 16 and these arms extend over and rest upon the cross rod 81 already mentioned, and when levers 104 are rocked they depress said rod and cause the release of the column actuators in the same manner as the depressing 25 of key 80 accomplishes that result.

The detents 37 are held in locking position relative to the accumulator wheels when partial strokes of the keys occur, by the 30 catches 42 which are prevented from moving out of the way of the detents by the pins 120 in the swinging hook stop levers 105 as will be noticed from Fig. 2.

It will be noted that the keys shown are 35 like those described in my Patents 982416 and 982417 that is to say: they are each made in two parts both adapted to be depressed by the finger when actuating the key the central part 111 being movable with 40 respect to the other and its actuation being necessary to the operation of the key, and the other part being side wings 112 which are incapable of yielding downward, because the tube 113 with which each key is 45 provided and which contains the lifting spring 114 for lifting the buttons 115 after each operation will then be arrested by the column actuator by reason of the normal locking of the actuator due to the engagement 50 of hook 50 with the side projection 51 on lever 52.

I claim:—

1. In a multiple order key driven calculating machine, the combination with the 55 numeral wheels, and keys for actuating said wheels, of means for normally locking the wheels, such means being released only at the end of complete downstrokes of the keys and during the ensuing upstrokes thereof.

2. In a multiple order key driven calcu-

lating machine, the combination with the numeral wheels, the keys for actuating said wheels, and the train of mechanism carrying motion from the keys to the wheels, of means for locking said mechanism and said wheels normally, such means being released only at the end of complete downstrokes of the keys and during the ensuing upstrokes thereof. 70

3. In a multiple order key driven calculating machine, the combination with a numeral wheel, and the series of keys actuating the wheel, of means for locking the wheel during down strokes of the keys, such means being releasable only at the end of complete down strokes and remaining released 80 during the ensuing upstrokes. 75

4. In a multiple order keyboard operating calculating machine, the combination with a numeral wheel, the series of keys actuating the wheel, and the mechanism for carrying motion from the keys to the wheel, of means for locking the wheel during down strokes of the keys, such means being releasable only at the end of complete down 90 strokes of the keys and remaining released during the ensuing upstrokes. 85

5. In a calculating machine, the combination with the numeral wheels, and keys for actuating said wheels, of means for locking the wheels, such means retaining their normally locking action on the wheels in case of partial strokes upon the keys and until 95 full strokes are given the same keys.

6. In a calculating machine the combination with the numeral wheels, the keys for actuating said wheels, and the train of mechanism carrying motion from the keys to the wheels, of means for locking said mechanism and said wheels normally, such 100 means retaining their locking action on said mechanism and wheels in case the strokes given the keys are only partial or incomplete and until full strokes are given 105 the same keys. 110

7. The combination in a calculating machine, of adding mechanism embracing a numeral wheel in each order, a key driven actuator for each wheel, a separate mechanism communicating motion from each actuator to the respective wheels, and a separate detent normally locking each of said communicating mechanisms, such detents releasing their locking action upon the completion of each down stroke given the actuators, and retaining such action in case the 115 strokes of the actuators are incomplete. 120

8. In a calculating machine, in combination, adding mechanisms for each order embraced in the machine, a plurality of keys 125 actuating said mechanisms and determining by their manipulation the amounts to be added, and locking detents one for each order, normally locking the adding mechanisms, such detents releasing 130

their locking action only at the completion of full strokes by the keys.

9. In a calculating machine, in combination, adding-mechanism, a multiple order keyboard driving mechanism having a plurality of orders of keys whose manipulation determines the amounts added, column actuators for each of the keyboard mechanisms, and devices substantially such as those described acting to lock said actuators when any key receives an incomplete down stroke.

10. A multiple order, key driven machine, having in combination adding mechanism, a column actuator in each order of the adding mechanism, keys driving said actuators, and locking devices substantially such as those described for all said actuators thrown into action when partial strokes are given the keys.

11. A multiple order, key driven machine, having in combination adding mechanism, a column actuator in each order of the adding mechanism, keys driving said actuators, and locking devices substantially such as described for all said actuators thrown into action when partial strokes are given the keys and a key for releasing said locking devices at will.

12. A multiple order key driven machine having in combination adding mechanism, a column actuator in each order of the adding mechanism, all provided with hooks, keys for driving the actuators, and swinging hooks adapted to engage the actuator hooks, and means for moving said swinging hooks into engagement with the actuator hooks when partial strokes are given the keys.

13. A multiple order key driven machine having in combination adding mechanism, a column actuator in each order of the adding mechanism, all provided with hooks, keys for driving the actuators; and swinging hooks adapted to engage the actuator hooks, and means for moving said swinging hooks into engagement with the actuator hooks when partial strokes are given the keys, and a key whereby such engagement may be terminated.

14. A multiple order, key driven machine having in combination adding mechanism, a column actuator in each order of the adding mechanism, keys for driving the actuators, means for locking all said actuators when any key is only partially depressed, and an exterior key or device adapted to release such locking means.

15. The combination with the column actuator and the actuating stop levers 27 and 28 and their operating keys, of the third lever 30 parallel to them and adapted to be pressed downward by said keys, said third lever rising to normal position when the strokes of the keys are only partially com-

plete, independently of the actuator and stop levers.

16. The combination with locking devices for locking the column actuators when partial strokes are imparted to the keys, of the lever 30 operating to control said locking devices when such partial strokes are made.

17. The combination with the column actuator and the stop levers and their actuating keys, of the lever 30 depressible by said keys, and adapted to rise to normal position independently of the others when any key receives a partial stroke, and locking mechanism controlled by said lever 30 when it rises, and adapted to lock the column actuator.

18. The combination in a multiple order key driven calculating machine, with the numeral mechanisms the keys and the column actuators, of means for locking both the numeral mechanism and the column actuators when incomplete strokes are imparted to the keys.

19. The combination in a multiple order key driven calculating machine, with the numeral mechanisms the keys and the column actuators, of means for locking both the numeral mechanism and the column actuators when incomplete strokes are imparted to the keys, and means for releasing the same.

20. The combination with the keys, the column actuators driven by the keys, and the means for locking the actuators in case of partial down strokes of the keys, of the canceling lever and means for releasing said locking means controlled by said lever.

21. The combination with the keys, the column actuators driven by the keys, and means for locking the actuators in case of partial down strokes of the keys, of a canceling lever and a key both adapted to be operated by the operator, and both connected to and controlling said means for locking the actuators, and each adapted to be used independently of the other, in releasing the actuators.

22. The combination in a multiple order, key driven calculating machine, of normally locked keys made in two parts, one movable with respect to the other and its operation being necessary to the release of the key, and normally locked column actuator driven by said keys, and released only when full down strokes are given the keys.

23. The combination in a multiple order key driven calculating machine, of normally locked keys made in parts, viz., a central part and outer part, one movable with respect to the other, and the central part being necessarily operated to release the key, and normally locked column actuators preventing independent movement by the outer part.

24. The combination in a multiple order

key driven calculating machine, of keys made in two parts movable with respect to each other and both adapted to be depressed by the finger at the same time, and normally locked column actuators acting to prevent the depressing of one of the parts independently.

25. The combination in a multiple order key driven calculating machine, of keys each having a central button and outer portions movable with respect to each other, and both depressible by the finger in operating the key, and a column actuator adapted to arrest said outer portions and prevent their being depressed independently of the central button.

26. The combination in a multiple order calculating machine of keys the operation of which determines the amounts added, column actuators driven by said keys, means for normally locking said actuators, and means for locking said actuators after partial strokes have been given the keys.

27. The combination in a multiple order calculating machine of keys the operation of which determines the amounts added, column actuators driven by said keys, means whereby said actuators are normally locked, but become released when a key in the same order therewith is struck, and means whereby the actuators become locked when incomplete or partial strokes are imparted to the keys.

28. In a multiple order, key driven calculating machine, the combination with the keys and the column actuators, of two mechanisms for locking the actuators, one effecting a normal locking, and the other locking the actuators when any key is only partially operated.

29. In a multiple order key driven calculating machine, the combination with the keys and the column actuators, of two separate mechanisms for locking the actuators, one mechanism acting normally, and the other coming into action after the first is released upon the making of incomplete strokes by the keys.

30. In a multiple-order key-driven calculating machine, the combination with the numeral wheels and keys for actuating said wheels, of means for normally locking the wheels, such means being released only to allow proper adding movements by the wheels.

31. In a multiple-order key-driven calculating machine, in combination, adding mechanism including numeral wheels and carrying devices adapted to permit said adding mechanism to receive prime actuations in a plurality of orders simultaneously, keys for actuating said wheels, and means for normally locking the numeral wheels

and adapted to release them only to allow proper movement of the wheels in adding.

32. In a multiple-order key-driven calculating machine, in combination, adding mechanism including numeral wheels and carrying devices adapted to permit said adding mechanism to receive prime actuations in a plurality of orders simultaneously, keys for actuating said wheels, and means for normally locking the numeral wheels and adapted to release them only when the wheels are otherwise in condition to properly add.

33. In a multiple-order key-driven calculating machine, in combination, adding mechanism including numeral wheels and carrying devices adapted to permit said adding mechanism to receive prime actuations in a plurality of orders simultaneously, keys for actuating said wheels, and means for normally locking the numeral wheels, such means being released only at the end of complete downstrokes of the keys and during the ensuing upstrokes.

34. In a multiple-order key-driven calculating machine, in combination, adding mechanism including numeral wheels and carrying devices adapted to permit said adding mechanism to receive prime actuations in a plurality of orders simultaneously, keys for actuating said wheels, and means for normally locking the numeral wheels, such means being releasable only at the end of complete downstrokes of the keys and remaining released during the ensuing upstrokes thereof.

35. In a multiple-order key-driven calculating machine, in combination; adding mechanism, including column actuators; and a locking mechanism adapted to lock other orders of the keys when a key of one order receives only a partial key-stroke, said locking mechanism including a trip-device auxiliary to the column actuator and having a movement independent of said column actuator.

36. In a multiple-order key-driven calculating machine, in combination; adding mechanism, including column actuators and carrying devices adapted to permit said adding-mechanism to receive prime actuations in a plurality of orders simultaneously; and a locking mechanism adapted to lock other orders of the keys when a key of one order receives only a partial key-stroke, said locking mechanism including a trip-device auxiliary to the column actuator and having a movement independent of said column actuator.
